DESIGN FOR A RADIO CABINET

Joseph Price, Chicago, Ill., assignor to Pacific Radio Corporation, Chicago, Ill., a corporation of Illinois

Application July 25, 1936, Serial No. 64,041

Term of patent 7 years

To all whom it may concern:

Be it known that I, Joseph Price, a citizen of the United States, residing at Chicago, Illinois, post office address 844 West Adams Street, Chicago, Illinois, have invented a new, original, and ornamental Design for a Radio Cabinet, of which the following is a specification, reference being had to the accompanying drawing, forming part thereof, in which:

I claim:

The ornamental design for a radio cabinet, as shown,

JOSEPH PRICE.
